(57) **CLAIM**

The ornamental design for a stroller with means of accommodating a child seat, as shown and described.

DESCRIPTION

FIG. 1 is a perspective view of a stroller with means of accommodating a child seat.

FIG. 2 is a right side elevational view thereof, the left side elevational view being a mirror image of the right side view.

FIG. 3 is a top plan view thereof.

FIG. 4 is a bottom plan view thereof.

FIG. 5 is a rear elevational view of the stroller with means of accommodating a child seat; and,

FIG. 6 is a front elevational view thereof.
